UNITED STATES PATENT OFFICE.

LEONARD H. WHEELER, OF CHICAGO, ILLINOIS, ASSIGNOR TO STEWART-WARNER SPEEDOMETER CORPORATION, OF CHICAGO, ILLINOIS, A CORPORATION OF VIRGINIA.

VAPOR INTERCEPTOR FOR VACUUM FUEL-FEED DEVICES.

Application filed June 12, 1922. Serial No. 567,572.

To all whom it may concern:

Be it known that I, LEONARD H. WHEELER, a citizen of the United States, residing in the city of Chicago, in the county of Cook 5 and the State of Illinois, have invented certain new and useful Improvements in Vapor Interceptors for Vacuum Fuel-Feed Devices, of which the following is a specification, reference being had to the accompanying 10 drawings, forming a part thereof.

The purpose of this invention is to provide in combination with a vacuum fuel feed device for an internal combustion engine means for intercepting any vaporized portion 15 of the fuel which may be drawn by the vacuum producing means, and preventing the same from being carried over through the source of suction. It consists in the elements and features of construction shown 20 and described, as indicated in the claims.

In the drawings:—

Figure 1 is a side elevation of a portion 25 of an internal combustion engine of an automobile, having a vacuum fuel feed device equipped with this invention, the engine being shown in dotted outline, except as to the intake manifold and carburetor, which are most directly concerned in the operation of the invention.

Figure 2 is an axial section of the intercepting device with an adjacent portion of the vacuum tank to which it is connected.

Figure 3 is an enlarged detail section of a baffle device in the interceptor.

Figure 4 is a vertical section of the valve fitting in the suction connection, section being made axial with respect to the pipe connection of said fitting.

Figure 5 is a diagrammatic view showing 40 a manually operable valve for determining the selection of the source of suction, the valve being in section axial with respect to its pipe connections.

In the drawings, the intake manifold of 45 the engine is represented at A and carburetor at A¹. B is the vacuum fuel feed tank of familiar construction, comprising the inner vacuum chamber, B¹, and the outer service chamber, B², with the annular space, B³, between the two, at the upper part. C is the fuel supply pipe leading from a low 50 level source, not shown, discharging into the

vacuum chamber, B¹. D is a pipe leading from the service chamber, B, to the carburetor, A¹. E is the oil circulating pump for 55 maintaining the supply of lubricant to the working parts of the engine. F is the intake pipe for the oil pump leading from the oil supply in the crank case as shown at f. F¹ is a shut-off and regulating valve in the 60 pipe, F. G, G¹, is a pipe leading from a T-fitting, F², in the pipe, F, for suction connection with the vacuum chamber, B¹, which connection is made through the vapor interceptor, H, hereinafter described. G² is 65 a suction pipe from the intake manifold, making junction with the pipe line, G¹, G², at the valve fitting, G⁴, hereinafter more particularly described. G³ is a shut-off and regulating valve in the pipe, G, intermediate the T-fitting, F², and the valve fitting, G⁴. For intercepting the vapor which may be drawn from the suction line from the 70 vacuum chamber, B¹, and preventing it from passing over to the source of suction whether 75 that source of suction be the intake manifold by way of the pipe line, G², or the oil circulating system by way of the pipe line, G, the T-fitting, F², and the pipe line, F, to the oil pump, E, the vapor interceptor, H, is 80 interposed in the suction line. This vapor interceptor consists primarily of a liquid trap, H¹, preferably formed interiorly of the water jacket, H², as seen most clearly in Figure 2. For the purpose of trapping the 85 liquid which may be condensed from the vapor or drawn over in globular form into the vacuum chamber, B¹, the suction pipe, D¹, makes a return bend for entering the trap, H¹, at the top; and from the top of 90 the trap the pipe, d, leads upward and makes a return bend for leading to the source of suction. This construction causes the deposit of any liquid globules drawn over with the air or vapor by the reversion 95 in the direction of the current which is forced by its downward entrance into and its upward exit out of the trap, H¹; at the same time the delay or slowing down of the current movement to the trap, on account of 100 the enlargement which said trap constitutes in the passage, permits condensation of the vapor; and this condensation is further assisted by the cooling water in the jacket, H².

Further to enforce the deposit in the trap of any liquid carried by the current, there is provided, preferably within the water jacket member, H^2 , in a short enlarged section, d^2 , of the pipe which extends within the jacket from the upper end of the trap to the top of the jacket chamber, mechanical baffling means, consisting of a plurality of baffles, J . These baffles consist each of a short tubular portion, J^1 , which is surmounted by a hood member, J^2 , having a downwardly-extending marginal flange, and spaced off from the upper end of the tubular portion by three short supporting posts, J^3 . These devices are mounted one above another centrally within the pipe section, d^2 , each by means of an annular hanger and spacer, K^1 ; exteriorly diametered for fitting within said pipe section, d^2 , and interiorly diametered at its smaller end for fitting tightly about and grasping the short tubular member, J^1 , thereby forming about said pipe member, J^1 , an annular pocket, K^4 , which gathers the liquid which may be forced out of the current by the baffling hood, J^2 , said hanger having a series of apertures, K^5 , through which the liquid is drained from the pocket into the trap, each of said baffles draining into the baffle below it and the lowest one delivering directly into the trap, as may be understood from the drawings. The trap, H , is mounted by means of the coupling, R , for delivery from its bottom into the upper end of the annular space, B^3 , constituting a portion of the service chamber of the vacuum chamber, a check valve, L , being provided at the discharge from the trap which opens for delivery of the liquid from the trap down into the said annular space, B^3 , and is seated upwardly by the suction. It will be understood, therefore, that the liquid accumulated in the trap so long as there is suction through the pipe, D^1 , will cease when the engine is stopped; and while the engine is at rest, the liquid which may have accumulated in the trap will drain into the service chamber, B^2 .

When both means of suction, viz., by means of oil pump through the pipes, G , G^1 , and from the intake manifold through the pipes, G^2 ; G^3 , are provided, it will usually be considered desirable to utilize the suction from the intake manifold, and that only, so long as that suction is adequate, the suction by means of the oil pump being brought into service only to supplement the deficiency of suction in the intake manifold by substituting the oil pump suction when the manifold suction is deficient. The valves, F^1 and G^3 , being adjusted so that the suction derived from the oil pump shall at its minimum be adequate for the maximum requirement for operating the vacuum tank, the valve fitting, G^4 , at the junction of the two lines of suc-

tion is designed to automatically cut off the suction of the manifold and utilize the suction of the oil pump only when the suction of the manifold falls below said minimum requirement; and, similarly, the range of the oil pump suction from minimum to maximum being narrow, the same device operates to cut off the oil pump suction whenever the manifold suction exceeds the oil pump suction. This is effected by means of check valves, N , N^1 , at the entrances of the pipes, G^1 and G^2 , respectively, to the upper end of the fitting, G^4 ; said check valves seating downward and being thereby normally seated by gravity, and opening upward in response to the suction in said pipe lines, respectively. Upon consideration of this construction, it will be seen that the suction in the pipe lines, G^1 or G^2 , which is the stronger, will produce in the passage g^4 of the valve fitting, G^4 , a vacuum superior to the vacuum produced in the other pipe line; and will thereby cause the valve at the entrance of said other pipe line to remain seated while the suction of the first pipe line,—the one having the stronger suction,—operates alone for drawing through the pipe line, G^1 .

Instead of relying upon the automatic determination of the source of suction which is effected by means of the pipe fitting, G^4 , and its check valves, N and N^1 , it may be preferred to control at will the selection of the source of suction as either manifold alone or the combination of the oil pump and the manifold with the means shown for deriving suction from whichever source affords the greater vacuum at any instant, in which case, usually the driver will cause the suction to be taken from the intake manifold alone whenever that suction is sufficient, and will shift it to the other suction line when the manifold suction becomes deficient. For this purpose, the construction shown in Figure 5 may be employed, in which the pipe, g^2 , leading from the intake manifold, and the pipe, g , which may be understood as leading from the valve, G^3 , and through the fitting G^4 , in the line from the oil pump, reach the three-way valve fitting, K , the said valve being adjustable to either position by means of the link 1 extending from the valve lever, 2, and so adapted for admitting the suction either from the manifold through the line, g^2 , or from the oil pipe line through the line, g .

It will be seen upon consideration that when the automatic valve device, G^4 , is employed, the stopping of the engine will not restore atmospheric pressure to the trap, unless means be provided for air to pass the valves, N and N^1 ,—and these valves are therefore each provided with a “bleed” or small aperture, n , which will not prevent the valves being seated as above described

in the passage in which the suction is less; and the suction leak through this port will be negligible.

I claim:—

- 5 1. In combination with an internal combustion engine, a vacuum fuel feeding device for the same and a liquid circulating pump, connections from the vacuum chamber of the vacuum fuel feed device to the liquid pump intake for producing vacuum by means of said pump; a gravity trap in said connection; drainage connection from the trap to the service chamber of the vacuum fuel feed device, and means in said 10 drainage connection for preventing suction-caused outflow from said service chamber.
- 15 2. In the construction defined in claim 1, foregoing, baffling devices in the portion of the conduit leading up from the trap and toward the source of suction, for arresting and deposit and drainage back to the trap of liquid particles carried in the vapor current.
- 20 3. In the construction defined in claim 1, foregoing; a water jacket enclosing the trap.
- 25 4. In the construction defined in claims 1 and 2, foregoing, a water jacket enclosing

the trap and the baffle-containing portion of the conduit.

5. In combination with an internal combustion engine, a vacuum fuel feeding device for the same, comprising a vacuum chamber and a service chamber or passage for delivery to the carburetor; suction connection from the vacuum chamber to a source of suction; a gravity trap for liquid in said suction connection, and drainage connections for such gravity trap back to the service chamber. 30 35

6. In the construction defined in claim 5, foregoing, a water jacket for cooling the trap for causing condensation and deposit of vapor sucked out of the vacuum chamber. 40

7. In the construction defined in claim 5, foregoing, the vacuum chamber having suction connection with two lines leading to sources of suction, and valve means for controlling at will said communication for deriving the suction alternatively through said two lines. 45 50

In testimony whereof, I have hereunto set my hand at Chicago, Illinois, this 7th day of June, 1922.

LEONARD H. WHEELER.
